United States Patent Office.

GEORGE S. FAULKNER, OF INDIANAPOLIS, INDIANA.

Letters Patent No. 99,176, dated January 25, 1870.

IMPROVEMENT IN HARNESS-OPERATING MECHANISM FOR LOOMS.

The Schedule referred to in these Letters Patent and making part of the same.

I, GEORGE S. FAULKNER, of Indianapolis, in the county of Marion, and State of Indiana, have invented certain Improvements in Harness-Motion for Looms, of which the following is a specification.

Nature and Objects of the Invention.

This invention relates to construction and arrangement of mechanism for actuating the treadles or harness-levers of looms, such mechanism being combined with and controlled in its movements by means of the ordinary pattern-chain or cylinder, so as to open the shed in the chain or warp, as may be determined in setting up the pattern-chain, the object being the production of a loom that is simpler and cheaper in construction than those heretofore in use, and equally efficient in weaving any desired pattern.

Description of the Accompanying Drawings.

Figure 1 is a side elevation of part of the front end of the loom, showing the form and arrangement of the upright treadles or harness-levers, and the construction and arrangement of my improved mechanism for operating or "calling" the treadles, and the relation thereto of the pattern-cylinder or chain by which the operation of the mechanism is controlled.

Figure 2 is an end view of the same.

Similar letters of reference indicate corresponding parts in the several figures.

As this invention relates wholly to the construction, arrangement, and operation of the device for actuating or "calling" the treadles or levers to which the harness is attached, the treadles being attached at the end of the machine, substantially as in the ordinary cam-loom, no more of the loom is shown in the drawing than sufficient to exhibit the relation of my device thereto.

General Description.

A is part of the front end of the frame.

B, the arches, which are made with a projection, B', one of which is left off to show more clearly the construction and arrangement of my device for operating the treadles C, the latter being hung on a pin or journal, a, as a fulcrum, in jaws projecting from the end of the frame, much in the usual manner.

e e are the shoes, against which the rocking cam D works, to give reciprocating motion to the treadles C.

The cams D, equal in number to the treadles, are hung on a shaft, i, and are provided with an arm, d, to the upper end of which one end of the longitudinal reciprocating jacks E is loosely pivoted, as shown.

The jacks E have square-shouldered notches on both the upper and lower edges, with which the transverse reciprocating bars F engage, to give them reciprocating motion, and thus imparting a rocking motion to the cams D.

The jacks E are raised and lowered to engage with reciprocating bars F, by means of lifting-jacks G, which are hung on a shaft or rod, n, the outer end working between guides o, which also serve as guides to the outer ends of the jacks E.

The pattern-chain or cylinder H is constructed in the usual manner, and hung under the lifting-jacks G, in such a manner that the pins S of the cylinder or the rolls of the chain will operate them, as hereafter described, the cylinder being arranged near the pin or fulcrum of the lifting-jacks, in order to secure sufficient movement of their outer ends without making the rolls of the chain too large, or pins in the cylinder too long.

The reciprocating bars F are operated by means of connecting-rods I, attached to their ends and to the ends of a vibratory lever, J, the movement of the latter being imparted from an eccentric, K, on the lower shaft L of the loom, being the same shaft that is usually employed to give motion to the pickers, and in some cases also to the harness in ordinary cam-loom, the eccentric working between lugs or shoes on the connecting-rod M, the upper end of which is attached to a short arm, J', attached at right angles to the centre of the vibrating lever J.

Motion is imparted to the pattern-cylinder or chain H by means of an eccentric, N, on the upper or crank-shaft O and connecting-rod P, attached by its upper end to one arm of the angular lever Q, to the other arm of which is attached a hooked pawl that engages with a ratchet on the shaft of the cylinder H or pattern-chain, carried in the usual manner.

The operation of my device to "call" or operate the harness to open the shed of the chain or warp, as required to weave any desired pattern, is as follows:

The pattern-cylinder H or chain being set up for any desired pattern, the pins S of the cylinder or rolls of the chain, as it is revolved, operate the lifting-jacks G, to raise and lower the jacks E to engage with the reciprocating bars F; thus, when the long pins S of the cylinder (or, if a chain is used, the large rolls,) raise the lifting-jacks G, which in turn raise the jacks E, so that the upper reciprocating bar F will engage with the notches in their upper edges and give them a longitudinal reciprocating motion, this in turn imparts a rocking motion to the cam D, the latter operating on the shoes e e of the treadles C, giving them the vibrating motion that raises and lowers the harness.

The notches in the upper and lower edges of the jacks E are arranged in the proper position, and made of sufficient length to allow them, and also the cams D, to remain motionless during a sufficient period, while the reciprocating bars F are returning on their backward stroke, to permit the pattern-chain or cylinder to be shifted; the outer ends of the cams in the mean time resting against the shoulder at the lower end of the

shoe, so as to hold the lever and harness motionless while the shuttle passes through the shed.

A short pin or small roll raises the jacks E just between the reciprocating bars F, so that neither of them will engage with the notches in the jacks, which, remaining motionless, leave the cams D and treadles C at rest. Where no pin or roll is used, the lifting and calling-jacks drop down, so that the lower reciprocating bar F will engage with the notches on the lower side of the jacks E, which operates them in the same manner as the upper reciprocating bar.

The advantages secured by the comparatively simple construction and arrangement of the rocking cams working on the shoes e e of the treadles C, these cams being actuated by reciprocating bars F that engage with longitudinal reciprocating jacks E, attached to the cams, all arranged to give the treadles positive reciprocating motion, having the requisite pauses to allow other parts of the loom to perform their functions, combined with the arrangement of the pattern-cylinder H, to perfectly control the operations of the cams so as to weave any desired pattern or figure without other change in the loom than to set up a pattern-chain according to the pattern required, will be appreciated by manufacturers and operators of looms.

It will also be apparent to weavers that by means of the arrangement of the rocking-cams D and shouldered shoes e e, the cloth may be woven face-side up or down, as may be required, without any change in any part of the mechanism other than to start the loom with the harness raised, for weaving the face-side down, and with them lowered to weave face-side up.

Claim.

1. The rocking-cams D, in combination with the shouldered shoes e e of the upright treadle C, all constructed and arranged substantially as and for the purpose set forth.

2. The combination of the cams D, hung in a vertical plane over the fulcrum of treadles C, lifting-jacks G, longitudinal reciprocating jacks E, reciprocating bars F, with the pattern-chain or cylinder H, all arranged and operating substantially as and for the purpose set forth.

GEORGE S. FAULKNER.
